UNITED STATES PATENT OFFICE.

EMIL KESSLER, OF BROOKLYN, NEW YORK.

SHEET-METAL TOY.

1,277,730.

Specification of Letters Patent. Patented Sept. 3, 1918.

Application filed January 8, 1916. Serial No. 70,909.

To all whom it may concern:

Be it known that I, EMIL KESSLER, a citizen of the United States, residing at Brooklyn, in the county of Kings and State of New York, have invented certain new and useful Improvements in Sheet-Metal Toys, of which the following is a specification.

This invention relates to sheet metal toys, and the principal object of the invention is 10 to provide a novel means for connecting the wheels of such toy to the axles or the like.

Other objects and aims of the invention, more or less broad than those stated above, together with the advantages inherent, will 15 be in part obvious and in part specifically referred to in the course of the following description of the elements, combinations, arrangements of parts, and applications of principles constituting the invention; and 20 the scope of protection contemplated will appear from the claims.

In the accompanying drawings, which are to be taken as a part of this specification, and in which I have shown a merely preferred form of embodiment of the invention, Figure 1 is a side elevation of a toy embodying the invention; Fig. 2 is a rear elevation of the same with parts removed and parts broken away; Fig. 3 is a partial 30 top plan view with certain of the parts removed; Fig. 4 is a detail perspective view of the means for fastening the wheel to the axle; Fig. 5 is an enlarged sectional view taken on the line 5—5 of Fig. 2 looking in the direction of the arrows; Fig. 6 is a side elevation of another form of toy embodying the invention; Fig. 7 is a front elevation of the same; and, Fig. 8 is an enlarged side elevation of the drive wheel and connected 40 parts.

Referring to the numerals on the drawings and particularly Figs. 1, 2 and 3, which show my invention as embodied in a toy hand car or the like, the numeral 9 indicates 45 the platform of the device having integral depending lugs 10 bent down at the sides to support the axles and having also an up-standing lug 11 punched out from the platform. The numeral 12 indicates the front 50 axle to which are secured the wheels 14. The rear or driving axle is in the form of a crank shaft 15 to which is pivotally connected a link 16, the other end of which is pivotally connected as at 17 to a lever 18, the latter 55 being pivoted on the lug 11. In the form shown in Fig. 1 the platform is provided

with a seat 19, on which is placed an effigy 20 connected to the lever 18 as indicated by the numeral 21, so that as the lever 18 oscillates there will be a corresponding movement 60 of the effigy. Each end of the crank shaft 15 has a squared portion as indicated in Fig. 5, and there is a U-shaped clip 22 provided with a squared opening 24 (see Fig. 4), which slips on to the squared end of the 65 shaft, at the inner side of each rear wheel. After these clips are in position on the shaft (and by the way they may be straight when they are slipped on and bent into the U-shape afterward, the wheels are slid on over 70 the ends of the shaft, and then the extreme ends of the shaft are flattened as indicated at 25 to prevent lateral movement of the 75 wheels. The ends of the U-shaped member 22 are bent so as to take between the spokes 75 of the wheel, and the clip is designed to prevent rotative movement of the wheel on the shaft. Another advantage is in the fact that by the use of this clip an accurate fit between the wheel and the shaft is not of 80 importance, and the aperture through the hub portion of the wheel may be considerably oversize. In Figs. 6, 7 and 8 the same form of clip is shown applied to a toy velocipede. The drive wheel is shown at 30 85 and passing through the hub portion thereof is a one-piece crank shaft 31, having also integral pedal portions 32. The fork is made in two parts 34 and 35, one leg on each side of the wheel. In assembling, the crank shaft 90 31 is first inserted through the hub portion of the wheel, the aperture in which may be considerably oversized to permit of this operation. Next, the clips 22 are positioned on the crank shaft, one on each side of the 95 wheel, and preferably at right angles to each other, as shown in Fig. 8, with their ends taking between the spokes of the wheel, and with squared or non-circular apertures of the clips engaged over correspondingly 100 formed portions of the crank shaft so that the clips and therefore the wheel will turn with the shaft. Next, the two parts of the fork, 34 and 35, are separately slid over the ends of the crank shaft to the Fig. 7 position, and then secured together at their upper ends, or to the frame of the velocipede, as indicated at 36. This is a simple and economical way of making a toy velocipede with a one-piece crank shaft. The crank 110 shaft is of the form illustrated, that is, it has a main portion, hangers at each end

of the main portion and pedal portions extending at right angles from the hangers. In positioning a wheel on this crank shaft the wheel is slipped over one of the pedal portions, past the bend between the pedal portion and the hanger and then past the bend between the hanger and the main portion of the shaft so that it takes its final position on the main portion of the shaft, and would be free to rotate thereon except for the provision of the clips. In the same way the clips and the parts of the fork are brought to position, one at a time, the squared or non-circular portions of the clips 10 engaging the correspondingly shaped portions of the main portions of the shaft, so that the clips and therefore the wheel which they engage, will rotate with the shaft, and the parts of the fork in each case coming 15 outside of the clips.

Inasmuch as many changes could be made in the above construction, and many apparently widely different embodiments of my invention could be made without departing 25 from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, might 35 be said to fall therebetween.

I claim:

1. In a device of the kind described, a shaft having a non-circular portion, a wheel rotatable with the shaft, and a U-shaped 40 clip having a non-circular aperture corresponding with the non-circular portion of the shaft and having its ends engaging the wheel.

2. In a device of the kind described, a 45 crank shaft extending through and at opposite sides of a wheel, a pair of clips on the crank shaft, and rotating therewith one at each side of the wheel and having their ends engaging the wheel. 50

3. In a device of the kind described, a crank shaft extending through and at opposite sides of a wheel, a pair of clips on the crank shaft, and rotating therewith one at each side of the wheel and having their ends 55 engaging the wheel, said clips being disposed at right angles to each other.

4. In a device of the kind described, a crank shaft extending through and at opposite sides of a wheel, a pair of clips on the 60 crank shaft, and rotating therewith one at each side of the wheel and having their ends engaging the wheel, and a two-piece fork, one part on each side of the wheel, and outside of the clips respectively. 65

5. In a device of the kind described, a shaft, a wheel on the shaft and a clip fixed on the shaft for rotation therewith and having a portion engaging the wheel.

In testimony whereof I affix my signature 70 in presence of two witnesses.

EMIL KESSLER.
